CRANKCASE BREATHER CAP

Herbert G. Kamrath, Flint, Mich., assignor to
General Motors Corporation, Flint, Mich., a
corporation of Delaware

Application February 25, 1935, Serial No. 8,046

4 Claims. (Cl. 121—194)

This invention relates to closure members, and more specifically to ventilating breather caps for crankcase ventilation on motor cars.

It is an object of my invention to provide a breather cap which will efficiently filter the air flowing into the crankcase of a motor upon a volumetric change in the crankcase.

It is a further object of my invention to provide a breather cap which will act as a condenser for oil vapors flowing from the crankcase.

A still further object is to provide a breather cap to fulfil the above requirements, and yet will be simple to construct and easily removed and attached to the breather pipe.

With these and other objects in view which will be evident in the light of the following disclosure, my invention resides in the construction as set forth in the specification and claims and illustrated in the accompanying drawing, in 20 which:

Figure 1 shows a vertical section through an internal combustion engine with my breather cap attached.

Figure 2 is a vertical section through the 25 breather cap taken on the line 2—2 of Figure 3.

Figure 3 is a bottom plan view of the device.

Figure 4 is a vertical section through the central portion of the cap only on line 4—4 of Figure 3 at right angles to the section shown in 30 Figure 2.

A conventional internal combustion engine 2 has a cylinder 4, piston 6, connecting rod 8, crankshaft 10 and crankcase 12. A breather pipe 14 extends from one side of the crankcase and 35 over the end fits the breather cap 16 which is the subject of my invention.

The cap per se comprises a central cylindrical member or tube 18 of a diameter to fit snugly over the end of the pipe 14 and having near its upper 40 end a series of openings 20 spaced throughout the circumference. An outer shell 22 which is cup-shaped has a pressed out portion 24 in its base which fits over the top of the member 18 when the cup is inverted over the cylinder. The 45 lower rim of the shell is spaced from the cylinder by an annular ring 26, the two edges of which are flanged as at 28 and 30, the inner flange 28 being secured to the cylinder by spot welding, and the outer flange 30 crimped up around the edge 50 of the shell. This annular ring has a series of circular holes 32 throughout its circumference, through which the air may flow. The outer shell 22 also has a series of louvres 34 in its lower portion for air flow.

Inside the cylindrical member 18 about mid-

way between its two ends is secured a bracket 36 which extends across the cylinder and to which is secured by a rivet a spring clip 38 shaped so that the legs press against the inside of the pipe 14 when the cap is in place to hold it securely. 5

The interior of the cylinder above the bracket 36 is filled with copper mesh 40 or other suitable pervious material, and the chamber formed between the cylinder and the outer shell is also filled with a similar material 42.

From this construction, it is evident upon a 10 volume change in the crankcase, that the air may enter either through the louvres 34 or through the circular openings 32 in the annular ring 26, then it passes up through the filtering 15 material 42, through the openings 20 and down through the filter material 40 to the crankcase. There is a large intake area provided which prevents plugging up. Also there is abundant 20 surface for filtering the dirt particles from the air as it goes into the crankcase. In case there is an increase in volume of the oil or oil vapor 25 in the crankcase, and there is a tendency of the vapor to flow from the crankcase, the oil vapor will pass up into the pervious material 40 and will condense, some air passing out of the cap and the oil returning to the crankcase. Some oil will, of course, be carried out into the outer 30 chamber and this will wet the filter material 42 which will increase its efficiency as a filter 35 and if sufficient oil passes into the chamber it will run down through the material 42 and wash off the dirt.

I claim:

1. A breather cap comprising, a central tube, 35 a larger one piece cup-shaped shell having the closed end thereof secured to one end of the tube and the sides thereof extending around the tube along its length, openings in the side of the tube adjacent the attachment to the shell, 40 a spacing member secured to the tube and the free end of the shell, louvres in the lower end of the shell, openings in the spacing member, a bracket secured across the tube substantially 45 midway between its ends and a spring clip secured to the bracket for assisting in securing the cap to a breather pipe.

2. A breather cap comprising a one piece cup-shaped shell having a depression in the closed end and louvres near the free end, a central 50 tube having openings in the walls thereof near one end, said end extending into said depression, a spacing member having openings therein, said member being secured to the tube and the free end of the shell, a bracket secured across the 55

tube substantially midway between its ends, pervious material in the tube above said bracket and in the space between said tube and said shell, and a spring clip secured to the bracket 5 for assisting in securing the cap to a breather pipe.

3. A breather cap comprising a one piece cup-shaped shell having louvres near the free end thereof and a depression in the closed end, a 10 central tube within said cup-shaped member having openings in the walls near one end, said end extending into said depression, a spacing member secured to said tube near the opposite end thereof and to the free end of said cup-shaped member, a bracket secured across the tube substantially midway between its ends, and pervious material in said tube above the bracket and in the space between said tube and the cup-shaped member.

4. A breather cap comprising a one piece cup-shaped shell having a depression in the closed end thereof, a central tube within said shell having openings in the walls thereof adjacent one end, said tube end extending into said depression, a spacer member fixed to the free end of said shell and to the tube near the end opposite the end in said depression, a bracket secured across the tube substantially midway between the ends and pervious material in said tube above said bracket and in the space between said tube and said cup-shaped member, there being openings in the spacer member and adjacent shell wall to permit air to flow within the structure. 15
